TRAILER FOR RECEIVING CAMPER UNITS
OR THE LIKE

Vernon J. Lundell, Cherokee, Iowa 51012

Filed Mar. 9, 1972, Ser. No. 333,402

Term of patent 14 years

Int. Cl. D12—10

U.S. Cl. D14—3 F

FIG. 1

FIG. 2

FIG. 3

FIG. 4

FIG. 1 is a perspective view of the trailer for receiving camper units or the like with the tailgate being omitted for ease of illustration showing my new design;

FIG. 2 is a front elevational view thereof, with the spring members and rear support jacks being omitted for ease of illustration;

FIG. 3 is a side elevational view wherein the opposite side is a mirror image thereof; and

FIG. 4 is a rear elevational view thereof with the tailgate attached and the front hitching member and support jacks being omitted for ease of illustration.

I claim:

The ornamental design for a trailer for receiving camper units or the like, substantially as shown and described.
